UNITED STATES PATENT OFFICE.

THOR RAJE, OF LOS ANGELES, CALIFORNIA.

TALKING-MACHINE RECORD.

1,275,087.

Specification of Letters Patent. Patented Aug. 6, 1918.

Application filed January 31, 1917. Serial No. 145,774.

To all whom it may concern:

Be it known that I, THOR RAJE, a citizen of the United States, residing at Los Angeles, in the county of Los Angeles and State of California, have invented a new and useful Improvement in Talking-Machine Records, of which the following is a specification.

My invention relates to talking machines and particularly to an improved form of record for use in connection with such machines and the primary object is to provide a record of such form that a greater length of groove may be provided, thus permitting the rendition of compositions of greater length than usual on other types of records.

Talking machines of the well known types are usually adapted for playing records of the disk and cylinder type, the disk machines having grown into more general favor in the recent years. The cylinder records which are usually employed in the cheaper machines and in offices and places of business are relatively short and small in diameter, and the length of the compositions which may be reproduced thereon are necessarily limited. The record grooves in the disk type of records decrease in diameter gradually as the reproduction of the composition progresses and thus, the speed of the disk being always the same, it is obvious that the groove speed will be greater near the periphery of the disk than at the inside and will gradually decrease as the needle of the reproducing element moves toward the center of the disk. This, of course, causes a corresponding change in the speed of the composition, and in many cases is unsatisfactory.

A further object of this invention, is therefore, to provide a record of such form that a maximum groove surface may be provided thereon and with the use of which the speed of the reproduction will be uniform throughout the length thereof.

A further object is to provide a form of record which is capable of use in series on a common mandrel or drum so that a lengthy composition may be played continuously from the series of records, as the reproducing needle progresses from one to the other of the series, or, several compositions may be played in consecutive or selective order without interruption, at the will of the operator. Other objects may appear as the description progresses.

Referring to the drawings, Figure 1 is an end view of one of my improved records in position on the drum. Fig. 2 is a fragmentary longitudinal section of several records in position on the drum and arranged for continuous or series playing. Figs. 3 and 4 are views similar to Fig. 2 but showing different forms of records and modifications thereof, which may be optionally employed in some instances to greater advantage than the form shown in Fig. 2. Fig. 5 is a longitudinal sectional elevation of a talking machine arranged for playing the records set forth in this application.

Similar characters of reference indicate the same and like parts throughout the specifications and the several views of the drawings.

Reference is had in the consideration of this invention, to a talking machine of my invention, for which I have applied for Letters Patent of the United States, filed August 17, 1916, Serial Number 115,402, in which application the form of record herein described is clearly shown and described. This application is a continuation in part of the former application.

My improved records 1 are of annular form and in comparison with the old style cylinder records are relatively narrow as to face. The diameter of the records is sufficient to insure several times the length of the grooves as compared with the old records. As shown in Fig. 5, a plurality of my improved records may be mounted in playing order upon a single drum or mandrel 2 so that the needle of the reproducing element 3 may pass from one to the other of the records 1 in continuous or selective order. The reproducer 3 is movable longitudinally of the drum 2, as described and shown in my former application.

As shown in Fig. 2, one end of each of the records 1 is beveled, as at 4, and the opposite ends are provided with recesses 5 which are beveled to conform to and are adapted to receive the beveled ends of the adjacent records. This form of record face will readily permit the travel of the reproducing needle from one to the other of the records and the joints between the records will not interfere with the movement of the needle. The large central openings 6 in the records fit snugly over the periphery of the drum 2 and a covering of felt or like substance 7 may be provided for the drum so as to frictionally hold

the records in position on the drum in a manner similar to that employed on the well known type of disk talking machines.

In Figs. 3 and 4, a modification is shown, 5 in which the playing faces of the records 1 are slightly tapered from one to the other end and the rear ends which are of the smallest diameter fit into the recesses 8 in the front ends 9. In this form of record a 10 curved shoulder is provided on each of the records above and covering the joint between it and the adjacent record, so as to prevent the interruption to the passage of the needle over the joints. The joints between 15 the records may be sliding as shown in Fig. 3, or, they may be threaded as shown in Fig. 4.

It is obvious that the horizontal faces of the records, as shown in Fig. 2 will provide 20 a uniform rate of speed for the rendition of any composition, while the slightly tapered faces of the other two forms will slightly vary the speed as the needle moves from left to right over the faces of the records. This 25 variation, however, will be so slight that it will scarcely be appreciable and either of the forms may be employed with equally good results, or nearly so.

My records may be used in machines 30 which will but slightly, if at all, increase the size of the case over that of the generally used talking machines in which but a single record may be played at a time. As stated, a substantially longer groove length 35 is provided on the annular type of record than on either the disk or cylinder types and longer compositions may be played, while the form of the record permits a relatively large number of the records to be held for 40 consecutive or selective use in a single machine, thus providing the maximum playing capacity in the minimum space.

In the use of the disk type of talking machine, the rate of progress of a composition 45 varies according to the position of the reproducing needle on the face of the disks, and as a minimum rate of speed is provided as the needle approaches the center of the disk, it would seem that the maximum speed 50 attained as the needle approaches the periphery of the disk is unnecessary. A record, therefore, of the annular type as

hereinbefore described may be operated at a slower rate of speed than the disks are operated with equally as good results and 55 without variation, thus providing a longer running time for the same length of grooves used on the disks, and likewise increasing the playing time.

Having thus described my invention, what 60 I claim is:

1. In combination with a horizontally disposed mandrel of uniform diameter, a plurality of relatively narrow record rings mounted on said mandrel, and having abutting edges, each of said rings having an annular projecting lip overlying the meeting edge of the next adjacent record ring on one side, whereby a needle moving upon one ring is transferred to the next adjacent ring at a 70 point inwardly from its edge, said record rings being provided with records in their faces, substantially as described.

2. In combination with a horizontally disposed mandrel of uniform diameter, a plurality of relatively narrow record rings mounted on said mandrel and having abutting edges, each of said rings having an annular projecting lip overlying the meeting edge of the next adjacent record ring on one 75 side, whereby a needle moving upon one ring is transferred by said lip to the next adjacent ring at a point inwardly from the edge thereof, said record rings having outer faces disposed at a slight angle to the mandrel longitudinally thereof, and having record grooves therein.

3. A reproducing record comprising a record ring substantially square in cross section and provided at one edge with an annular projecting lip tapering inwardly from the outer surface thereof, and adapted to overlie the edge of an abutting record ring fitting therewith, the outer surface of said ring and the surface of said lip being provided with a record groove, substantially as 90 described.

Signed at Los Angeles, in the county of Los Angeles and State of California, this 3d day of January, 1917.

THOR RAJE.
